DESIGN FOR A PLATE OR SIMILAR ARTICLE

John I. Bahl, Canton, Ohio, assignor to Bahl
Potteries, Inc., Carrollton, Ohio, a corporation of Ohio

Application March 27, 1941, Serial No. 99,935

Term of patent 14 years

To all whom it may concern:

Be it known that I, John I. Bahl, a citizen of the United States, residing at Canton, in the county of Stark and State of Ohio, have invented a new, original, and ornamental Design for a Plate or Similar Article, of which the following is a specification, reference being had to the accompanying drawing, forming a part thereof.

Fig. 1 is a plan view of a plate, showing my new design.

Fig. 2 is a transverse sectional view of the plate, as on line 2—2, Fig. 1.

Fig. 3 is a fragmentary transverse sectional view of the plate, as on line 3—3, Fig. 1.

I claim:

The ornamental design for a plate or similar article, substantially as shown.
